UNITED STATES PATENT OFFICE

SAMUEL HALBERG AND HARRY L. HALBERG, OF BROOKLYN, NEW YORK

SEWING MACHINE ATTACHMENT

Application filed June 4, 1928. Serial No. 282,846.

The present invention is concerned with the provision of a sewing machine attachment of the general character disclosed in the prior patent of Samuel Halberg, No. 1,607,532 dated November 16, 1926. The patented device included means for supporting a roll of tape or the like adjacent a sewing machine for guiding the tape under the needle of the machine and for selectively manually severing the tape at any time.

In accordance with the present invention the construction of the attachment has been materially improved. In the first place, the entire attachment is now provided with means for holding it securely against vibration in use. The construction of the tape roll holder has been improved to permit the ready insertion of a tape roll into the hole. The tape cutter mechanism has been rendered much more positive and accurate, and means has been provided for preventing any retrograde movement of the tape at any time. With the old machine a certain amount of back lash sometimes developed in the tape roll which would cause the free end of the tape to slip back after it had been settled.

Other objects of the present invention are to provide a sewing machine attachment of simple, practical construction, which will be rugged, durable and efficient in use, well suited to the requirements of economical manufacture, convenient manipulation and ready attachment to, or removal from a sewing machine.

With the above noted and other objects in view, the invention consists in certain novel features of construction and combinations and arrangements of parts as will be more fully hereinafter set forth and pointed out in the claims. The invention may be more fully understood from the following description in connection with the accompanying drawings, wherein—

Fig. 1 is a perspective view of a sewing machine showing our improved attachment in applied position.

Fig. 2 is a vertical sectional view through the tape holder.

Fig. 3 is a side elevational view in vertical section of the tape guide and cutter.

Fig. 4 is a transverse sectional view on the line 4—4 of Fig. 3.

Fig. 5 is a top plan view of the tape guide.

Fig. 6 is a longitudinal sectional view therethrough on the line 6—6 of Fig. 5. 55

Fig. 7 is a detail showing the arrangement of the gauge plate relatively to the needle and presser foot.

In the drawings we have used the reference numeral 10 to designate generally a sewing machine of conventional construction including the usual arm 11, head 12 and needle plate 13. This sewing machine is adapted to be mounted on a table or other suitable support, and the attachment of the present invention is supported partly by the machine and partly by the table in order that vibration may be reduced to a minimum. 60

A generally L-shaped bracket includes a vertical standard 14 formed at its lower end 70 with a foot 15 adapted to be screwed or otherwise rigidly secured to the table (not shown) which supports the sewing machine. The horizontal arm 16 of the L-shaped bracket projects at right angles from the top of the standard 14 and is adapted to carry the tape roll holder, best seen in Figs. 1 and 2.

The tape roll holder includes a stationary bracket 17 rising from the arm 16 and carrying a stationary plate 18 upon which is mounted a hub 19 for the tape roll 20. Preferably, the hub 19 is adjustably carried on a screw 21 projecting through the bracket 17 and plate 18; this screw being held against rotation by a spring finger 22 entering a notch in the screw head. Cooperating with the plate 18 to constitute the open sided tape roll holder is a plate 23 hingedly mounted as at 23' for pivotal movement about its lower edge. Preferably the hinge 23' is a spring hinge so that the plate 23 will automatically be restored to the illustrated vertical position after it has been depressed or swung down to permit application or removal of the tape roll 20. 85 90

A tape guiding member, cut, stamped and bent from a single strip of metal or otherwise suitably formed includes a horizontal portion which we have designated generally by the reference numeral 24, and a vertical 100

portion indicated generally at 25. One end of portion 24 of the tape guiding unit is secured as at 26 to the arm 16, while the intermediate portion of the member 24 is secured to a bracket 27 which in turn is fixed to the arm 11 of the sewing machine by a U-bolt 28 encircling the arm. This bolt 28 may incidentally serve to clamp one end of a bracket arm 29 integral with the vertical portion 25 of the tape guiding unit.

The free end of the tape being led from the tape roll 20 is first passed under a strap 30 affixed to the portion 24 of the tape guide. Strap 30 preferably defines with the tape 15 guide member 24 a channel for the tape, the tape being additionally guided in one or more loops or straps 31 arranged at intervals along the guide member 24, 25. A flat spring 32 is arranged under the strap 30 and secured at 20 one end to the strap by a securing device 33. The free end of the spring 32 bears against the tape passing under the strap and is serrated or toothed as at 34 in order to positively block any retrograde movement of the 25 tape. Tension on the spring 32 is regulated by a thumb screw 35 mounted in the strap 30, the screw in turn being held against rotation by one end of a bow spring 36.

Arranged in horizontal position and carried by the vertical section 25 of the tape guiding unit is a cutter mechanism in the nature of a pair of scissors including a stationary blade 37 and a pivoted blade 38, the latter at its free end being provided with an 35 operating thumb piece 39 and a coiled contractile spring 40 normally holding the movable blade in the inactive position shown in the drawings.

To sever the tape, the operator simply 40 places a finger on the member 39 and forcibly swings the movable blade 38 to closed position. Full closing of the blade which might result in the two blades sticking together is prevented by the engagement of the stud member 41 with the thumb piece 39.

Secured upon the needle plate of the machine in any suitable manner as by a thumb screw 42 is a gauge plate 43 including a vertical flange 44 disposed in parallelism with the path of travel of the tape and material 45 to which the tape is attached as the tape and material are passed under the needle 46. A finger 47 projecting beyond the flange 44 serves to guide the end of the tape under the presser foot 48 and its associated needle.

By virtue of the above described construction, retrograde movement of the tape incidental to cutting thereof, is absolutely prevented, and the tape may be accurately fed from the floating tape roll at all times.

The construction of the tape roll holder is such that a new roll may be readily replaced. The entire attachment is free from vibration and readily adjustable as well as being readily bodily removable from the machine.

Obviously various changes and alterations might be made in the general form and arrangement of the parts described without departing from the invention. Hence we do not wish to limit ourselves to the details set forth, but shall consider ourselves at liberty to make such changes and alterations as fairly fall within the spirit and scope of the appended claims.

We claim:

1. A tape guiding attachment for sewing machines including a generally L-shaped member including an approximately horizontal portion to be disposed over a sewing machine arm and receive tape from a roll, a substantially vertical portion for guiding the tape to the sewing mechanism, tape guiding straps on each portion of the L-shaped member, and a toothed tensioned spring finger under one strap preventing retrograde movement of the tape.

2. A tape guiding attachment for sewing machines including a generally L-shaped member including an approximately horizontal portion to be disposed over a sewing machine arm and receive tape from a roll, a substantially vertical portion for guiding the tape to the sewing mechanism, a stationary cutter blade fixed to the vertical portion and a pivoted cutter blade connected thereto and normally spring held in open position.

3. A tape guiding attachment for sewing machines including a generally L-shaped member including an approximately horizontal portion to be disposed over a sewing machine arm and receive tape from a roll, a substantially vertical portion for guiding the tape to the sewing mechanism, a stationary cutter blade fixed to the vertical portion, a pivoted cutter blade connected thereto and normally spring held in open position, a thumb piece on the pivoted blade for manually moving the same to closed position, and a stop engaging the thumb piece to prevent full closing and sticking of the blades.

4. A tape guiding attachment for sewing machines, including an L-shaped tape roll supporting member, having a horizontal portion adapted to be disposed over the sewing machine arm, bracket means on the free end of said horizontal portion for securing the same to the sewing machine arm, tape guiding straps on said horizontal portion, a toothed tensioned spring finger under one of said tape guiding straps, the toothed portion of said spring finger being adapted to contact with the tape intermediate a pair of said tape guiding straps, a substantially vertical portion for guiding the tape to the sewing mechanism, a stationary cutter blade fixed to the vertical guiding portion and an associated cutter blade pivotally connected thereto.

5. A tape guiding attachment for sewing machines, including an L-shaped tape roll

supporting member, having a horizontal portion adapted to be disposed over the sewing machine arm, bracket means on the free end of said horizontal portion for securing the same to the sewing machine arm, tape guiding straps on said horizontal portion, a toothed tensioned spring finger under one of said tape guiding straps, the toothed portion of said spring finger being adapted to contact with the tape intermediate a pair of said tape guiding straps, a substantially vertical portion for guiding the tape to the sewing mechanism, a stationary cutter blade fixed to the vertical guiding portion, an associated cutter blade pivotally connected thereto and normally spring held in open position, a thumb piece on the pivoted blade for manually moving the same to closed position, and a stop engaging the thumb piece to prevent full closing and sticking of the blades.

6. A tape guiding attachment for sewing machines, including an L-shaped tape roll supporting member having a horizontal portion adapted to be disposed over the sewing machine arm, bracket means on the free end of said horizontal portion for detachably securing the same to the sewing machine arm, tape guiding straps on said horizontal portion, a toothed tensioned spring finger under one of said tape guiding straps, the toothed portion of said spring finger being adapted to contact with the tape intermediate a pair of said tape guiding straps for preventing retrograde movement of the tape, a substantially vertical portion for guiding the tape to the sewing mechanism, a stationary cutter blade fixed to the vertical guiding portion, an associated cutter blade pivotally connected thereto and normally spring held in open position, a thumb piece on the pivoted blade for manually moving the same to a closed position, a stop for engaging the thumb piece to prevent full closing and sticking of the blades, and an additional tape guiding member adapted to be adjustably mounted on the needle plate of the sewing machine for guiding the tape under the presser foot of the sewing mechanism.

Signed at Bklyn, N. Y., in the county of
50 Kings and State of New York, this 19th day
of April, A. D. 1928.
